UNITED STATES PATENT OFFICE.

GEORGE HOWARD NEIDLINGER, OF BROOKLYN, NEW YORK.

NIPPLE.

SPECIFICATION forming part of Letters Patent No. 577,199, dated February 16, 1897.

Application filed November 18, 1895. Serial No. 569,309. (No model.)

To all whom it may concern:

Be it known that I, GEORGE HOWARD NEIDLINGER, a citizen of the United States, residing in Brooklyn, in the county of Kings and State of New York, have invented a new and Improved Sucking-Nipple, of which the following is a specification.

My invention relates to an improvement in sucking-nipples; and it consists of a rib or series of ribs running in a spiral direction on the inside of the nipple, formed integrally therewith, and made before the rubber is vulcanized. The ribs, acting as a spring, serve to keep the nipple normally extended and prevent the collapse of said nipple, the ribs being formed to cross each other at an angle when pressed together, leaving space between the ribs for food to flow from the bottle.

In the drawings, Figure 1 is a side elevation of the nipple. Fig. 2 is a vertical transverse section, and Fig. 3 is a horizontal section taken on line $\alpha\alpha$ in Fig. 1.

A is the nipple, made of soft rubber and adapted to be clasped over the neck of a nursing-bottle.

B B are the inwardly-projecting ribs or corrugations, running spirally in a longitudinal

direction and acting as a spring or springs which tend to distend the bulb of the nipple.

The nipple is made in one piece with the 30 ribs or corrugations constituting part of the same, all being formed in a suitable mold before the rubber is vulcanized.

It is obvious that I may employ diagonal ribs which are not spiral. Therefore I do not 35 limit myself strictly to the form shown.

In the top of the nipple are formed one or more holes C for the escape of food.

What I claim as new, and desire to secure by Letters Patent, is—

A soft nipple for nursing-bottles, provided with a perforation at the top adapted to be clasped over the vent of a nursing-bottle, and provided in the inside with ridges curved at the ends in opposite directions, the ridges on 40 opposite sides being arranged to cross each other at an angle, whereby the complete collapse of the nipple is prevented, substantially 45 as described.

GEORGE HOWARD NEIDLINGER.
